CLAIM

The ornamental design for an electrical plug adapter, as shown and described.

DESCRIPTION

FIG. 1 is a front, bottom, right perspective view of an electrical plug adapter showing my new design;

FIG. 2 is a back, top, right perspective view thereof;

FIG. 3 is a front, top, right perspective view thereof;

FIG. 4 is a front elevational view thereof;

FIG. 5 is a back elevational view thereof;

FIG. 6 is a right side elevational view thereof;

FIG. 7 is a left side elevational view thereof;

FIG. 8 is a bottom plan view thereof;

FIG. 9 is a top plan view thereof;

FIG. 10 is a front, top, right perspective view thereof, shown with the receptacle module secured to the base and the cord wrapped along the back of the electrical plug adapter;

FIG. 11 is a back, top, left perspective view thereof, shown with the receptacle module secured to the base and the cord wrapped along the back of the electrical plug adapter;

FIG. 12 is an exploded back, top, right perspective view thereof, shown with an insertable plug;

FIG. 13 is an exploded front, top, right perspective view thereof, shown with an insertable plug;

FIG. 14 is a back, top, right perspective view thereof, shown with an insertable plug in an inserted state;

FIG. 15 is a front, top, right perspective view thereof, shown with an insertable plug in an inserted state;

FIG. 16 is an exploded back, bottom, left perspective view thereof, shown with an insertable plug and an insertable extension cord;

FIG. 17 is an exploded front, top, right perspective view thereof, shown with an insertable plug and an insertable extension cord;

FIG. 18 is a back, bottom, left perspective view thereof, shown with an insertable plug and an insertable extension cord, both in an inserted state; and,

FIG. 19 is a front, top, right perspective view thereof, shown with an insertable plug and an insertable extension cord, both in an inserted state.

The broken lines showing the insertable plug in FIGS. 12-19 and the insertable extension cord in FIGS. 16-19 depict

(Continued)

environmental subject matter that forms no part of the claimed design. All other broken lines depict portions of the electrical plug adapter that form no part of the claimed design.

In FIGS. 1-7 and 12-15, the cord connecting the receptacle module to the base of the electrical plug adapter is shown broken away for illustration purposes. The full length of cord is shown in FIGS. 10, 11, and 16-19.
